CINEMATOGRAPH PROJECTOR FIRE TRAP

Thomas Edward Glynn, Saskatoon, Saskatchewan, Canada

Application January 3, 1938, Serial No. 183,205

7 Claims. (Cl. 88—17)

My invention relates to improvements in cinematograph fire traps, an object of this invention being to provide a device of the character herewithin described by the use of which a fire started in a cinematograph projector between the upper and lower film magazines through the ignition of that portion of the film strip which is passing from the one magazine to the other may be prevented from spreading to either magazine by sealing off the same from the force of the fire.

A further object of my invention is to provide a device of the character herewithin described by which the ignited portion of the film is severed from the roll remaining in either one of the magazines.

A further object of my invention is to provide a device of the character herewithin described which may be located within either one or both of the film magazines by being secured to the circumscribing wall thereof, or which may be located in any position between the upper and lower film magazine.

A further object of my invention is to provide a device of the character herewithin described which is actuated by the fusion of a strand of material extending between the flanges of one of the film sprockets, this action causing a number of spring catches to move outwardly, thereby grounding a current which actuates a solenoid, which in turn releases a spring-held cutting knife which severs the portion of the film between the film magazines from that which is within the same and seals the contents of the said magazine.

A further object of my invention is to provide a device of the character herewithin described which is of simplified construction, is simple to install and which cannot easily become out of order.

With the above more important objects in view and such other minor objects as may appear as the specification proceeds, my invention consists essentially in the arrangement and construction of parts all as hereinafter more particularly described, reference being had to the accompanying drawings, in which:

Fig. 1 is a side view of a cinematograph projector showing a portion of the upper and lower film magazines, my film cutting assembly being shown partly in section with part of the projector itself being also shown in section.

Fig. 2 is a longitudinal cross section of my film cutting assembly.

Fig. 3 is a plan view of my film cutting assembly.

Fig. 4 is a longitudinal section of my film sprocket used in association with the film cutting assembly and solenoid.

In the drawings like characters of reference indicate corresponding parts in the different figures.

My invention consists of a cutting assembly A, a solenoid assembly B, and a specific form of film sprocket assembly C, and of these three parts I will first describe my cutting assembly.

This consists of a cutter block 1, which is suitably secured as by means of the bolts 2 to the circumscribing wall of one or other of the film magazines 3, although I would mention here that this assembly may, if desired, be located at any convenient point within the film chamber 4, preferably at one end or the other thereof.

Extending along the sides of the cutter block 1 is a pair of cutter guides 5 and 6, a projecting flange portion 7 extending thereover to prevent dislodgment of the cutter later to be described.

Extending across the forward end 8 of the cutter block and spaced from the base plate 9 thereof by means of a spacing block 10 of the configuration clearly illustrated by phantom lines in Fig. 3 of the drawings accompanying this specification is a cutter plate 11 provided upon either side with brackets 12 between which is mounted for rotation a film roller 13, which assists in guiding the strip of film 14 through a slot 15 clearly illustrated in Fig. 3 of the drawings accompanying this specification, formed upon the plate 9.

My cutter 16 is provided with an obliquely disposed cutting edge 17 and with side members 18 and 19 clearly illustrated in Fig. 3 of the drawings accompanying this specification which are designed to run within the recesses formed between the flanges 7 and the edges of the base plate 9.

To the rear end of my cutter is attached a block 20, provided with a pair of orifices 21, through each of which extends a spring guide 22, these spring guides being secured upon an end wall 23, secured to the rear end of the cutter block and extending upwardly thereacross. A cutter tension spring 24 extends around each of the members 22 between the portions 20 and 23 so that the tendency is for the cutter 16 to be forced to the left with respect to Figure 3 of the drawings accompanying this specification, thereby cutting the film 14 passing through the slot 15 and sealing the latter.

Upstanding bearings 25 are provided upon the portion 20 in a substantially central position thereupon, a pivoted cutter lock 26 being secured by means of a pin 27 passing therethrough and 5 extending between the bearings 25, this lock being of the configuration clearly illustrated in Figs. 2 and 3 of the drawings accompanying this specification, and when the cutter is held back in the position shown it will be seen that the lock 10 26 engages with a stationary catch 27, secured in alignment with the lock upon the upper surface of the end-wall 23.

Adjacent one end of the member 20 is an insulating block 28, the same being suitably secured 15 to the cover 16 and within which is a spring terminal 29, the terminal being provided with an enlarged head 30, a light spring 31, surrounding the stem of the terminal and bearing at one end against the head and at the other end against 20 the block. Secured to the member 5 is a second insulating block 32, the member 5 being recessed at this point to receive the same, the block itself being of the configuration clearly illustrated in Figure 3 of the drawings accompanying this 25 specification.

A solenoid lead 33 and a collector ring lead 34 extend up to the block 32 terminating thereat in a solenoid lead terminal 35 and a collector ring lead terminal 36, the two terminals extending 30 through the block 32 but being insulated from each other, the exterior faces thereof being in alignment so that the head 30 of the spring terminal 29 may bear against both of these members, thereby completing an electrical connection 35 at this point.

Having now described my cutter assembly I will next describe my film sprocket assembly most clearly illustrated in Fig. 4 of the drawings accompanying this specification.

40. In this assembly I make use of the ordinary film sprocket 37 but process the flanges 38 and 38' thereof in the manner and for the purpose now to be described. A number of drillings 39 are formed through the flange 38 adjacent the 45 periphery thereof and into these drillings I plug a number of fusible-link pegs 40 of the configuration clearly illustrated, while somewhat larger drillings 41 are formed adjacent the periphery of the flange 38', these somewhat larger drillings, 50 however, extending only a portion of the way through the thickness of the flange. I then continue to drill through the flange 38' with a bit of the same size as that used for the drillings 39 and I now insert into the apertures thus formed 55 a plurality of spring-actuated fusible-link pins 42 of the configuration clearly illustrated in Fig. 4 of the drawings accompanying this specification, from which it will be seen that the same are somewhat similar in configuration to the pegs 40 but are provided with an encircling flange 43 against which bears a light coil spring 44, one 60 end of the spring bearing against the end of the enlarged drilling 41, and it will be understood that the members 42 are free to slide within their 65 apertures, whereas the pegs 40 are held rigidly.

I now lace a strand of fusible material 45 across the sprocket between the flanges, the material being held in the notches 46 and 47 of the pegs and the pins respectively.

70. In connection with this fusible material I should mention that I may use a continuous laced strand or may employ a number of links of the same and in either case it should be clearly understood that the lacing is sufficiently tight or 75 the links sufficiently short to hold the pins 42

in the position shown in Fig. 4 of the drawings accompanying this specification, in which the springs 44 are held in compression and the outer end of each of the pins is flush with the end of the sprocket.

The sprocket is mounted upon the usual spindle 49, which is suitably journaled in the usual bearing 50, the sprocket 37 being held fast against the spindle 49 by means of a set-screw 51. Adjacent the sprocket and extending around the 10 portion 52 (which may if desired be reduced in diameter for this purpose) is positioned a collar 53 of insulating material, the collar being also held fast by means of a set-screw 54. The collar 53 is recessed to receive a bronze collector 15 ring 55, and attached to the collector ring is the opposite end of my collector ring lead 34, it being clearly understood at this point that under normal circumstances the bronze ring 55 is out of contact with the pins 42.

Having now described my film sprocket assembly, I will next describe my solenoid assembly.

This consists of a solenoid 56 best illustrated in Fig. 1 of the drawings accompanying this specification, the same being attached to a mounting block 57 secured upon the outer surface of the circumferential wall of the film magazine 3 although it is to be understood that if desired, the solenoid may be placed in any other suitable position for the purpose of co-acting with my cutter 30 assembly.

Through the centre of the solenoid and through a passageway formed within the bearing block 57 extends a release pin 58, the outer end of which is pointed as illustrated, the pin being 35 normally maintained in the position clearly illustrated in the drawings accompanying this specification.

A solenoid input lead 59 extends from the solenoid to the usual main, while the solenoid lead 33 already described, extends between the terminal 35 and the solenoid.

Having now described the various component parts of my invention, its operation will be set forth.

In the event of a portion of the film within the film chamber 4 becoming ignited by the heat of the lamp or through other reasons, the fusible material 45 will become severed. When this happens, the pins 42 will shoot out under the 50 influence of the springs 44 and will engage and make contact with the collector ring 55, whereby current passing through the lead 34 will be grounded upon the metal part of the projector, which will have the effect of energising the solenoid, thereby causing the release pin 58 to move to the left, thereby releasing the lock 26 from the catch 27, will cause the cutter 16 to snap across and sever the film and seal the slot 9. As soon as this happens it is obvious that contact 60 will be broken between the terminals 35 and 36 whereupon the current will flow normally again through the solenoid.

When it is desired to reset the cutter assembly the sprocket assembly must be re-fused or if a 65 pair of sprocket assemblies are being used they will both be re-fused. Alternatively a new assembly or assemblies may be inserted. The cutter is then drawn back again to the position illustrated in the drawings accompanying this specification, after which the lock will be brought into engagement with the stationary catch and the release pin moved to the left. The device is now again ready for an emergency.

It is obvious, of course, that when the pointed 75

end of the release pin 58 bears against the bevelled under-side 60 of the lock 26, the same is bound to rotate upwardly about the pivot pin 27' thus automatically releasing it from the catch 27.

5 It should clearly be understood that while I have shown in Fig. 1 of the drawings accompanying this specification only one cutting mechanism A located within the upper film magazine 3, I may if I so desire place one of these mechanisms 10 in the lower film magazine as well. In this case, an additional sprocket assembly C may be employed adjacent the lower end of the film chamber 4, or, on the other hand, the one sprocket assembly may be employed to actuate the two 15 cutting mechanisms. It should be furthermore clearly understood that if desired my cutting mechanism or mechanisms may be placed without the film magazine as upon the exterior surface thereof or within and adjacent either end of the film chamber to seal off the ends thereof.

20 Since various modifications can be made in the above invention, and many apparently widely different embodiments of same, made within the scope of the claims without departing from the spirit and scope thereof, it is intended that all 25 matter contained in the accompanying specification shall be interpreted as illustrative only and not in a limiting sense and I desire only such limitations placed thereon as are specifically expressed in the accompanying claims.

30 What I claim as my invention is:

1. In a cinematograph projector fire trap assembly and in combination with a film cutting mechanism and an adjacent solenoid, a film 35 sprocket mechanism and an adjacent current carrying element, said film sprocket mechanism consisting of the combination with a film sprocket of a movable contact normally spaced from the said current carrying element, said contact being 40 designed to move into contact with said element upon the ignition of a strip of film within a film chamber whereby said solenoid is energised and said film cutting mechanism actuated to cut off the ignited strip of film from the film within 45 an adjacent magazine.

2. In a cinematograph projector fire trap assembly and in combination with the film cutting mechanism and an adjacent solenoid thereof, a film sprocket mechanism and an adjacent current carrying element, said film sprocket mechanism consisting of the combination with the said film sprocket of a plurality of outwardly movable 50 spring actuated contacts extending through one of the flanges of said sprocket, and a plurality of stationary pegs secured to the opposite flange, said contacts being provided each with a recess, a strand or link of fusible material extending 55 across the body of said sprocket, around said pegs and through the recess within each of said contacts normally to restrain said contacts against outward movement, said contacts being free to spring outwardly upon the fusing of said link or strand to make contact with said current carrying element, thereby energising said solenoid to 60 actuate said film cutting mechanism.

65 3. In combination with an electrically actuated

film cutting assembly for a cinematograph projector, a rotatable film engaging sprocket mechanism, comprising a sprocket, a movable contact upon said sprocket, a fusible element attached to said contact, and an adjacent contact whereby 5 ignition of a strip of film in the film chamber of said projector releases said movable contact against said adjacent contact thereby actuating said cutting assembly.

4. A cinematograph projector fire trap assembly comprising in combination, a film cutting mechanism, said mechanism comprising a body portion mounted within a film magazine of a projector and having a slot formed therein through which a strip of film may pass, a cutter slidably mounted upon said body portion for movement across said slot, an obliquely disposed cutting edge formed upon the forward edge of said cutter, guide rods secured at one end thereof to said body portion, the forward ends of said rods projecting 20 slidably through apertures provided in a portion of said cutter, coil springs mounted about said guide rods and extending between said cutter and said body portion, releasable locking means for holding said cutter normally in a retracted position against the tension of said springs, comprising a stationary catch secured to said body portion, a movable catch engageable with said stationary catch and pivotally mounted upon said cutter, the free end of said movable catch being 25 sharply bevelled, a solenoid secured adjacent said body portion and having its longitudinal axis in alignment with the bevelled end of said movable catch, a releasing pin slidably positioned within said solenoid, the forward end of said pin being 30 pointed and positioned adjacent the bevelled end of said movable catch, whereby said movable catch is released and said springs permitted to force said cutter across said slot when said solenoid is energised, a solenoid circuit closing mechanism positioned within the film chamber of said projector, said mechanism being designed to close 35 the solenoid circuit upon ignition of a strip of film in said chamber.

5. The device as defined in claim 4 in which 40 said circuit closing mechanism comprises a rotatable film engaging sprocket mechanism, a heat responsive element comprising part of said mechanism, whereby said mechanism is actuated to close the circuit of said film cutting assembly 45 upon ignition of a strip of film in the film chamber of said projector.

6. In combination with the device as defined in claim 4, a solenoid circuit opening mechanism, said mechanism being automatically actuated 50 upon release of said cutter.

7. The device as defined in claim 2 in which 55 said current carrying element comprises an annular ring positioned concentrically with said sprocket and insulated from the body of said projector, the circuit extending from a source of electrical energy through said solenoid and to said element, being grounded upon fusion of said link of fusible material and consequent contact 60 of said movable contacts with said ring.

65 THOMAS EDWARD GLYNN.
